UNITED STATES PATENT OFFICE.

GEORGE H. RIVES, OF BROOKLYN, NEW YORK.

PAD FOR SHOE-SHINING FOOT RESTS.

Application filed August 23, 1921. Serial No. 494,701.

To all whom it may concern:

Be it known that I, GEORGE H. RIVES, a citizen of the United States, and a resident of New York, borough of Brooklyn, in the county of Kings and State of New York, have invented certain new and useful Improvements in a Pad for Shoe-Shining Foot Rests, of which the following is a full, clear, and exact specification.

10 This invention relates to a class of devices adapted to be used in conjunction with shoe polishing apparatus.

At public shoe polishing establishments it is customary to employ brackets having 15 rests for supporting the feet of persons while their shoes are being polished. These rests are usually made of metal, and owing to the tendency of the shoes to slip sidewise back and forth on the rests the wearer is 20 often considerably inconvenienced and frequently the person accomplishing the work of polishing is injured by the hands accidentally contacting with the edges of the metal foot rests.

25 My invention has for its object primarily to overcome these objections by providing a pad of rubber or other suitable resilient material which in practice is applied on the foot rests of shoe shining stands to obviate

30 the liability of the shoe of a person when being polished from slipping on the rest, and which is of a form whereby the hands of the person doing the polishing will be protected from likelihood of injury by preventing contact with the edges of the foot 35 rest proper. This is accomplished mainly by providing a pocket element having two integral resilient walls of shapes to permit the pad to be removably applied to the foot

40 part of the rest of a shoe shining bracket, and one of the walls is flat to lie upon the top of the rest to prevent a person's shoe from slipping when being polished while the other wall is substantially U-shaped in 45 cross section for covering the edge and the underside of the foot rest for serving as a protector against the hand of the person accidentally contacting with the shoe when doing the polishing.

50 A further object of the invention is to provide a pad for shoe shining foot rests of a simple and efficient construction which may be made in any suitable size and shape.

With these and other objects in view the 55 invention will be hereinafter more fully de-

scribed with reference to the accompanying drawings forming a part of this specification in which similar characters of reference indicate corresponding parts in all the views, and will then be pointed out in the 60 claims at the end of the description.

In the drawings, Figure 1 is a fragmentary view showing an elevation of a shoe polishing stand with one form of pad embodying my invention applied thereto. 65

Fig. 2 is an enlarged top plan of the pad.

Fig. 3 is an enlarged inverted plan of the device.

Fig. 4 is an enlarged sectional view taken on the line 4—4 of Fig. 3, and 70

Fig. 5 is an enlarged perspective view of the locking element used in the device.

The device or pad has a pocket element 10 adapted to be removably applied on the foot rest 11 of the bracket 12 which is commonly 75 used on public shoe polishing stands, as 13, and both the bracket and foot rest are usually made of metal of a size and shape whereby the shoe of a person tends to slip thereon when the shoe is being polished. 80 Moreover, it frequently happens that the hands of the person doing the polishing are injured by accidentally contacting with the edge of the metal foot rest especially in event of the shoe slipping. 85

The pocket element 10 may be made of rubber or other suitable resilient material, and this element is formed with a wall or plate 14 which is preferably flat having a toe portion 15, a body portion 16 and a shank portion 17. The resilient plate 14 may be somewhat larger than the foot part of the metal rest 11, and this plate may be of a thickness to provide a suitable cushion, while its top face may be ribbed or otherwise roughened, as at 18, to cause the sole of the shoe when placed thereon to frictionally cling to the pad. 90

Integrally formed with the underside of the toe portion 15 of the wall or plate 14 is 100 the second wall 19 of the pocket element. The wall 19 is preferably U-shaped in cross section as well as being approximately semi-elliptic in shape to provide a spanning member 20 and an edge wall or member 21 which extends from the spanning member to the plate 14 so as to embrace the edge of the toe part 15 of the plate. The entrance, as 22, to the pocket of the element 10 is thereby under the body portion 16 of the 110

plate 14 so that when the pocket element is applied to the foot rest 11 the toe part of the rest is inserted in the pocket with the plate 14 being disposed upon the top face 5 of the plate. The edge of the toe part of the metal foot rest 11 will then be covered by the resilient semi-elliptic wall member 21 of the pocket element for serving as a protector to safeguard the hands of the person 10 polishing the shoe from contacting with the edge of the foot rest.

The plate 14 and the U-shaped wall 19 being preferably made of rubber with the wall of medium thickness and this wall is 15 strengthened by providing on its edge at the pocket 22 a rib 23, and to prevent tendency of the wall 19 from premature tearing or splitting from the plate 14 at the entrance 22 where the wall and plate intersect are 20 provided two gussets, as 24 and 25, both made of rubber of somewhat triangular shapes extending from the spanning member 20 of this wall to the plate 14 at the ends of the member 21 of the wall. The resilient 25 plate 14 is of a length so that its body portion 16 and shank portion 17 extends beyond the entrance 22 of the pocket, and the shank portion is adapted to be detachably fastened to the foot rest 11 by a locking element, as 26. 30 The locking element 26 may be of any appropriate type, though the form of the locking element shown has a metal strap 27 of a shape and size to encompass the shank portion 17 of the plate 14 and the 35 edge parts of the foot rest 11. The end portions of the strap 27 are bent right-angularly centrally of the underside of the foot rest 11 to provide two spaced lugs 28 and 29 which have registered holes there- 40 through. In the registered holes of the lugs 28 and 29 is a bolt 30 with a screw head 31 adapted to be moved into engagement with the lug 28, and the threaded end of the bolt protrudes beyond the lug 29. On this, 45 threaded protruding end of the bolt 30 is a nut, as 32, adapted to be screwed into engagement with the lug 29 of the strap 27 for moving the lugs 28 and 29 toward each other which in turn will tighten the strap 50 on the shank part of the plate 14 of the pad and on the foot rest 11. The shank part of the plate 14 of the pad will then be detachably held to the foot rest 11 for serving to prevent tendency of the shoe, as 55 23, of a person when being polished from slipping on the foot rest as well as serving to protect the hands of the person doing the polishing process from contacting with the edge of the foot rest. 60 In the foregoing description, I have embodied the preferred form of my invention, but I do not wish to be understood as limiting myself thereto, as I am aware that modifications may be made therein without de- 65 parting from the principle or sacrificing any

of the advantages of this invention, therefore, I reserve to myself the right to make such changes as fairly fall within the scope thereof.

Having thus described my invention, I 70 claim as new and desire to secure by Letters Patent:—

1. A pad of the character described, comprising a pocket element having two integral resilient walls of shapes for adapting 75 the pad to be removably applied over the foot part of the rest of a shoe shining bracket and one of the walls being flat to lie upon the top of the foot rest, while the other wall is substantially U-shaped in cross section 80 for covering the edge and the underside of the foot rest, said upper wall being adapted to be detachably fastened to the foot rest, and reinforcing gussets at the entrance of the pocket element where its walls intersect. 85

2. A pad of the character described, comprising a resilient flat plate having a body portion, a toe portion and a shank portion, said plate being adapted to be removably 90 applied upon the top of the foot rest of a shoe shining bracket, a resilient pocket element on the underside of the toe portion of the plate for receiving the toe portion of the foot rest, said pocket element having a 95 substantially semi-elliptic side wall protruding from the plate for serving as a protector by covering the edge of the toe part of the front rest, and means adapted to detachably fasten the shank of the plate to 100 the foot rest.

3. A pad of the character described, comprising a resilient flat plate having a body portion and a toe portion, said plate being adapted to be removably applied upon the 105 top of the foot rest of shoe shining bracket, an elastic pocket element on the underside of the toe portion of the plate for receiving the toe part of the foot rest, said pocket element having a wall spaced from the resilient 110 plate and having a side wall extending to the resilient plate for covering the edge of the toe part of the foot rest, a strengthening rib on the edge of the wall of the pocket element spaced from the resilient plate, and 115 elastic reinforcing gussets at the entrance of the pocket where its side walls intersect with the resilient plate.

4. A pad of the character described, comprising a resilient flat plate having a body 120 portion, a toe portion and a shank portion, said plate being adapted to be removably applied upon the top of the foot rest of a shoe shining bracket, an elastic pocket element on the underside of the toe portion of 125 the plate for receiving the toe part of the foot rest, said pocket element having a wall spaced from the resilient plate and having a side wall extending to the resilient plate for covering the edge of the toe part of the 130

foot rest, a strengthening rib on the edge of the wall of the pocket element spaced from the resilient plate, elastic reinforcing gussets at the entrance of the pocket where its side wall intersects with the resilient plate, a separate strap adapted to be removably arranged over the shank of the resilient plate and over the foot rest, and a bolt adjustably connecting the ends of the strap so that the strap may be tightened for detachably fastening the resilient plate to the foot rest. This specification signed and witnessed this 22 day of August, A. D. 1921.
